(57) **CLAIM**

I claim the ornamental design for a headboard, as shown and described.

DESCRIPTION

Cross-reference is made to U.S. Design patent application Ser. No. 29/566,377 entitled "Headboard for a Patient Bed", which is filed on the same day as the present application and is expressly incorporated herein by reference.

FIG. 1 is a front perspective view of the design of the headboard;

FIG. 2 is a front elevation view of the design of FIG. 1;

FIG. 3 is a rear elevation view of the design of FIG. 1;

FIG. 4 is a top plan view of the design of FIG. 1;

FIG. 5 is a bottom plan view of the design of FIG. 1;

FIG. 6 is a first side elevation view of the design of FIG. 1, with the opposite, second side elevation view being a mirror image of the first side elevation view; and,

FIG. 7 is a rear perspective view of the design of FIG. 1. The features shown in broken lines depict environmental subject matter only and form no part of claim design.
